(57) **CLAIM**

The ornamental design for a small arms transmitter mounting bracket for a multiple integrated laser engagement system, as shown and described.

DESCRIPTION

The invention described and claimed herein may be manufactured, used, and licensed by or for the U.S. Government for U.S. Government purposes.

FIG. 1 is a front view of a small arms transmitter mounting bracket for a multiple integrated laser engagement system of my new design;

FIG. 2 is a left side view thereof;

FIG. 3 is a back view thereof;

FIG. 4. Is a right side view thereof;

FIG. 5 is a top view thereof;

FIG. 6 is a bottom view thereof; and,

FIG. 7 is a perspective view thereof.
